DESIGN FOR A BATHING SUIT

Alfred L. Flesh, Piqua, Ohio, assignor to The Piqua Hosiery Company, Inc., Piqua, Ohio, a corporation of Ohio

Application September 26, 1935, Serial No. 58,729

Term of patent 3½ years

To all whom it may concern:

Be it known that I, Alfred L. Flesh, a citizen of the United States, residing at Piqua, county of Miami, and State of Ohio, have invented a new, original, and ornamental Design for a Bathing Suit, of which the following is a specification, reference being had to the accompanying drawing, forming part thereof.

and Figure 3 is a side view of a bathing suit,
showing my new design.

I claim:

The ornamental design for a bathing suit, as shown.

ALFRED L. FLESH.
